RELEASER VESSEL FOR DAIRY EQUIPMENT

Lloyd F. Bender, Hayward, Wis.

Filed Oct. 2, 1963, Ser. No. 76,832

Term of patent 3½ years

(Cl. D23—1)

FIGURE 1 is a side elevational view of a releaser vessel for dairy equipment embodying my new design;

FIGURE 2 is a top plan view thereof;

FIGURE 3 is a front view thereof; and

FIGURE 4 is a bottom view thereof but on a reduced scale.

The undisclosed side of the releaser vessel is a mirror image of the side shown in FIGURE 1.

The rear of the vessel is the same in appearance as the front view except it has no outlet conduit as seen in the front view.

I claim:

The ornamental design for a releaser vessel for dairy equipment, substantially as shown and described.
